(57) **CLAIM**

The ornamental design for a pot lid, as shown and described.

DESCRIPTION

FIG. 1 is a front elevation view of a pot lid, showing our new design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines shown in FIGS. 5-7 depict portions of the pot lid that form no part of the claimed design. The shade lines in the figures are utilized to illustrate surface contours of the claimed design and do not depict surface ornamentation.

1 Claim, 7 Drawing Sheets
